US00D995574S

(12) **United States Design Patent** (10) **Patent No.:** **US D995,574 S**
(45) **Date of Patent:** **** Aug. 15, 2023**

(54) **LAND CLEARING TOOL INTERFACE**

(71) Applicant: **Fecon, LLC**, Lebanon, OH (US)

(72) Inventors: **Jeffrey Stanley**, Lebanon, OH (US);
Robert Hentz, Hamilton, OH (US)

(73) Assignee: **Fecon, LLC**, Lebanon, OH (US)

(**) Term: **15 Years**

(21) Appl. No.: **29/869,758**

(22) Filed: **Jan. 9, 2023**

Related U.S. Application Data

(60) Division of application No. 29/839,827, filed on May 24, 2022, now Pat. No. Des. 976,965, which is a division of application No. 29/764,864, filed on Jan. 4, 2021, now Pat. No. Des. 956,828, which is a division of application No. 29/650,678, filed on Jun. 8, 2018, now Pat. No. Des. 914,064, which is a division of application No. 29/611,032, filed on Jul. 18, 2017, now Pat. No. Des. 821,455, which is a division of application No. 29/571,065, filed on Jul. 14, 2016, now Pat. No. Des. 795,931, which is a division of application No. 29/560,329, filed on Apr. 5, 2016, now Pat. No. Des. 791,195, which is a division of application No. 29/466,991, filed on Sep. 13, 2013, now Pat. No. Des. 757,124, which is a continuation of application No. 12/918,677, filed as application No. PCT/US2009/034872 on Feb. 23, 2009, now Pat. No. 8,540,033.

(57) **CLAIM**

The ornamental design of a land clearing tool interface, as shown and described.

DESCRIPTION

FIG. 1 is a front, right, perspective view of a land clearing tool interface;

FIG. 2 is a rear, left perspective view thereof;

FIG. 3 is a top view thereof;

FIG. 4 is a right side view thereof, with a left side view being a mirror image of FIG. 4;

FIG. 5 is a bottom view thereof; and,

FIG. 6 is a front view thereof.

The broken line showing in the drawings is included for the purpose of illustrating portions of the land clearing tool interface and forms no part of the claimed design.

1 Claim, 2 Drawing Sheets
